UNITED STATES PATENT OFFICE.

GEORGE W. BARTLETT, OF YONKERS, NEW YORK, ASSIGNOR TO THE
ALEXANDER SMITH & SONS CARPET COMPANY, OF SAME PLACE.

DESIGN FOR CARPET.

SPECIFICATION forming part of Design No. 27,125, dated May 25, 1897.

Application filed April 5, 1897. Serial No. 630,874. Term of patent 3½ years.

To all whom it may concern:

Be it known that I, GEORGE W. BARTLETT, of Yonkers, county of Westchester, State of New York, have invented and produced a certain new and original Design for Carpets, 5 fully described and represented in the following specification and the accompanying drawing, forming a part of the same.

The design is intended to be worked into or 10 upon carpets or similar fabrics in such colors as may be desired; and I do hereby declare that the drawing accompanying this specification conveys to any one skilled in the art 15 of carpet weaving and manufacture a clear understanding of the same and is sufficient to enable such person to use my invention.

The design is characterized by the curved stem and leaf form A, terminating in a scroll B and corresponding leaf form C.

What I claim as new, and desire to secure 20 by Letters Patent, is—

The design for carpets, substantially as shown and described.

In testimony whereof I have hereunto set my hand in the presence of two subscribing 25 witnesses.

GEO. W. BARTLETT.
